UNITED STATES PATENT OFFICE.

WILLIAM F. HAUSSTEIN, OF LYNDHURST, NEW JERSEY, ASSIGNOR TO THE KEUFFEL & ESSER COMPANY, OF HOBOKEN, NEW JERSEY, A CORPORATION OF NEW JERSEY.

CALCULATING-MACHINE.

No. 882,560.

Specification of Letters Patent. Patented March 24, 1908.

Application filed November 10, 1904. Serial No. 232,115.

To all whom it may concern:

Be it known that I, WILLIAM F. HAUSSTEIN, a citizen of the United States, residing at Lyndhurst, in the county of Bergen and State of New Jersey, have invented certain new and useful Improvements in Calculating-Machines, of which the following is a specification.

This invention relates to calculating machines, such as that which forms the subject matter of U. S. Patent to Alexander Rechnitzer, Number 809,075, granted January 8, 1906.

In that machine the operations of addition, subtraction, multiplication and division are performed and the machine in order to warn the operator when the calculating machinery is not in proper position to be operated, has an indicator which displays at the proper and improper times for starting the machine appropriate legends, as for instance the words "Right" and "Wrong" respectively. Notwithstanding this warning however, there is danger that the operator may overlook it and start up the machine when the word "Wrong" is displayed and thus break or disarrange many working parts.

The object of this invention is to make it impossible to start the machine unless the word "Right" is displayed by the indicator showing that all of the parts are in correct operative position and the invention consists in providing such a machine with mechanism for carrying out this object.

In the accompanying drawings, in which I have illustrated the mechanism comprised in this invention and so much of the original machine as is necessary to properly disclose the construction and operation of the various parts, Figure 1 is a top plan view, parts being shown broken away, parts being in dotted lines, and the starting lever being in section. Fig. 2 is a transverse vertical section on a plane to the right of the locking bar and starting lever looking to the right. Fig. 3 is a front elevation, the front of the casing being removed and parts being broken away. Fig. 4 is a top plan view of the locking bar and connecting parts, parts being omitted and others broken away, the locking bar being in unlocked position, and Fig. 5 is a similar view with the locking bar in locked position.

In the original machine a casing incloses the parts, of which the top plate is shown at

6 and said top plate is provided with a longitudinal slot 7 having two forwardly extending lateral branch slots 8 and 9 and end spaces 10 and 11. A starting lever 12 is secured to a shaft 13 journaled in bearings 14 secured to the base of the machine. This starting lever which projects upward through the slot 7, will start the machine to perform the operation of addition when moved into the branch slot 8, subtraction when moved into the branch slot 9, multiplication when moved into the end space 10, and division when moved into the end space 11. In the original machine there also appears a shaft 15 carrying a suitable number of numeral wheels, as at 16, said shaft being connected with another shaft 17 by suitable gearing 18 and provided with a segment 19 bearing the words "Right" and "Wrong" to indicate through a suitable sight hole 20, (Fig. 1,) the positions of the various moving parts of the calculating mechanism, in order to warn the operator not to start the machine, and thus more or less damage it, unless the proper positions are indicated by the exposure of the word "Right."

In carrying out the object of this invention, the mechanism which I shall now describe has been added. On the shaft 15, which carries the numeral wheels and indicating segment, is secured a crank arm 21 carrying a wrist pin 22 which enters a curved slot 23 in an arm 24 secured on a shaft 25 which shaft also carries a finger 26. On the starting lever shaft 13 is secured a locking plate 27 provided with notches 28 in its outer edge, to coöperate with a locking bar 29 slidably secured to the base of the machine by screws 30 passing through slots 31 into the base. At that end of the locking bar in line with the finger 26 there is provided a recess 32 having an inclined wall 33 and at the opposite end, said bar is provided with an upwardly projecting lug 34 having a forwardly projecting tooth 35 at its top and a spline 36 on the underside of said tooth. The locking arm is normally held in inoperative position by a spring 37.

The indicating mechanism and all of the parts on the shafts 15 and 25 to and including the finger 26 are mounted in the sliding carriage 38 which is provided with wheels, or rollers 39, resting upon the base of the machine, while the starting lever, its shaft and all attached parts are on the stationary base

of the machine. In order to start the machine, the starting lever must either be rocked, with its shaft, to bring it into one of the lateral branch slots 8 or 9, or it must be moved longitudinally of the machine, (with its shaft) to bring it into one of the end spaces 10 or 11.

When the shaft 15 and its numeral wheels are in correct position (which would indicate that all connecting parts were also in correct position) the crank arm 21 (Fig. 2) would depend substantially vertically and its wrist pin 22 would be in the center of the curved slot 23 in the arm 24 causing the segment 19 to show up the word "Right" in the sight hole 20 and the finger 26 to assume the position shown in dotted lines in Fig. 2. In this position this finger, at the end of the sliding movement of the carriage would pass into the recess 32 of the locking bar 29 and the machine would be started for another operation by either rocking or sliding the starting lever, as before described. Should, however, the parts at any time get into a wrong position, the shaft 15 will be turned to show "Wrong" in the sight hole (Fig. 1) the wrist pin on the crank arm 21 would move toward one end of the curved slot (Fig. 2 full lines) and the finger 26 be moved to the full line position of Fig. 2. In this position as the carriage is reaching the end of its travel the said pin will strike the inclined wall 33 of the recess 32 in the locking bar 29 and cause the bar to move into a locking position with the tooth 35 overlapping the locking bar 27 thus preventing the starting of the machine to add or subtract by rocking the starting lever. The spline 36 engaging in one of the notches 28 of the locking block 27 also prevents the starting of the machine to multiply or divide by preventing the sliding of the starting lever with the shaft 15.

Thus it will be seen that not only will the operator be warned by the display of the word "Wrong" on the indicating segment, but the starting lever will be rigidly locked to prevent the starting of any new operation.

When the word "Wrong" shows up, the numeral wheel shaft may be turned to zero by the means provided in the old machine, which will shift the parts so as to display the word "Right" and to bring the finger 26 into operative position as before described.

From an inspection of Fig. 2 it will be seen that the wrist pin 22 will shift the finger 26 to the "wrong" or operative position when said wrist pin is moved from the center to either end of the curved slot 23, thus locking the machine when the numeral wheel shaft is displaced or slightly wrong in either direction, the segment displaying "Wrong" through the sight hole in either displacement.

What I claim as new is:—

1. In a machine of the character described, the combination with a shaft, numeral wheels

thereon, and an indicator on said shaft bearing an appropriate legend, of a slidable rock shaft, a lever secured thereto, and means for locking the shaft and lever against movement in any direction when said legend is displayed. 70

2. In a machine of the character described, the combination with a shaft, numeral wheels thereon, and an indicator on said shaft bearing an appropriate legend, of a slidable rock shaft, a pivoted lever, and means for locking the lever against pivotal movement when said legend is displayed. 75

3. In a machine of the character described, the combination with a shaft, numeral wheels thereon, and an indicator on said shaft bearing an appropriate legend, of a laterally movable lever, and means for locking the lever against lateral movement when said legend is displayed. 80

4. In a machine of the character described, the combination with a numeral wheel shaft, and an indicator thereon bearing an appropriate legend, of a lever adapted to be moved to various positions and means governed by the movement of the numeral wheel shaft for locking the lever against any movement when the indicator is in position to display the legend. 90

5. In a machine of the character described, the combination of a numeral wheel shaft, an indicator thereon bearing an appropriate word, a lever adapted to be moved to various positions, a locking bar to engage the lever to prevent any movement thereof, a pivoted finger adapted to operate the locking bar, and connections between the shaft and the pivoted finger whereby the position of the indicator controls the position of the finger. 95

6. In a machine of the character described, the combination of a numeral wheel shaft, an indicator thereon bearing an appropriate word, a lever adapted to be moved to various positions a locking bar to engage the lever to prevent any movement thereof, a pivoted finger adapted to operate the locking bar, a slotted arm rigidly connected with said finger, and a crank arm on the numeral wheel shaft carrying a pin operating in the slotted bar. 100

7. In a machine of the character described, the combination with a right and wrong indicator, of a slidable rock shaft, a lever fixed thereon, and means controlled by the indicator to prevent the sliding of the shaft. 110

8. In a machine of the character described, the combination with a right and wrong indicator, of a slidable rock shaft, a lever fixed thereon, and means controlled by the indicator to prevent the rocking of the shaft. 115

9. In a machine of the character described, the combination with a right and wrong indicator, of a slidable rock shaft, a lever fixed thereon, and means controlled by the indicator to prevent the rocking of the shaft. 120

cator to prevent the sliding or rocking of the shaft.

10. In a machine of the character described, the combination of an indicator, a rock shaft, a locking block fixed thereon, a lever also fixed on the shaft adapted to be moved to various positions by which movement the shaft is rocked, a locking bar controlled by the indicator, and a projecting finger on the locking bar adapted to overlap the locking block when the bar is moved forward thus locking the lever by preventing the rocking of the shaft.

11. In a machine of the character described, the combination of an indicator, a sliding rock shaft, a locking block fixed thereon having a notch in its edge, a lever also fixed on the shaft adapted to be moved to various positions by sliding it with the shaft, a locking bar, controlled by the indicator, and a spline carried by the locking bar adapted to enter the notch in the locking block and prevent the sliding of the shaft

when the locking bar is in its forward position.

12. In a machine of the character described, the combination of an indicator, a sliding rock shaft, a locking block fixed thereon having a notch in its edge, a lever also fixed on the shaft adapted to be moved to various positions by sliding or rocking it with the shaft, a locking bar controlled by the indicator, and a tooth carried by said locking bar and provided with a spline, said tooth being adapted to overlap the locking block to prevent the rocking of the shaft and the spline being adapted to enter the notch in the locking block and prevent the sliding of the shaft when the locking bar is in its forward position.

In testimony whereof I affix my signature in presence of two witnesses.

WILLIAM F. HAUSSTEIN.
